CASE PACKING MACHINE AND METHOD

Melvin Salvasser, P.O. Box 101, Reedley, Calif.

Filed Feb. 10, 1955, Ser. No. 487,407

8 Claims. (Cl. 53—26)

This invention relates to a method and apparatus for packing a plurality of articles of substantially uniform size and shape, such as cartons, boxes, bags, and the like, in a case or shipping container.

In packaging most soft goods, it is common to put up such goods in packages of a size suitable for use by the retail consumer. These packages are usually small enough to be held in one hand, and are reasonably regular in configuration. For the purposes of shipment to the retailer and display by him, these small packages are normally packed in predetermined multiples in a case or shipping container. The case may contain a dozen, or perhaps two dozen small packages, and it is conventionally tailored to fit such a predetermined number of packages.

Assembling the packages into multiples and inserting them into the container by hand is a tedious and time consuming job, and therefore, known apparatus has been used to perform this task. Such apparatus is ordinarily complicated and expensive to operate and service, or performs only part of the task.

Many known methods and machines are capable of forming multiples in one or two of the principal orthogonal directions but not in all three of such directions. With such methods and machines it is possible to arrange only a single layer of small packages for insertion into a case.

Furthermore, most of the known machines are capable of assembling only packages which have a rigid, regular shape such as cartons and boxes. Some products, such as sugar and flour, are packed in paper bags which tend to become rounded due to the hydraulic effect of the loose material. Others, such as frozen food products, tend to bulge their containers by expanding upon freezing. These types of articles or packages, although substantially uniform in size and shape, are not capable of supporting themselves in vertically stacked relationship, because of their slight irregularities. Therefore, known case packing machines usually fail to adequately operate thereon.

By the method and machine of this invention, it is possible to readily assemble and insert in to a case a number of small packages arranged in layers, each layer containing multiples of such packages in two directions.

It is therefore an object of this invention to provide a novel method for assembling a predetermined number of articles into a predetermined arrangement for insertion into a case.

Another object of this invention is the provision of apparatus for carrying out the above method.

It is yet another object of this invention to provide a method of packing cases which is fast and relatively easy to perform.

Still another object of this invention is the provision of a method for arranging a number of articles of substantially uniform size and shape in a case lot comprising a plurality of stacks, each stack comprising a plurality of tiers, and each tier comprising a plurality of articles.

2

It is a further object of this invention to provide a machine for automatically arranging a plurality of articles of substantially uniform size and shape into tiers, stacks of a plurality of said tiers, and a case lot of a plurality of said stacks, and for inserting said case lot into a case.

It is still a further object of this invention to provide a machine for assembling packages in a predetermined stacked relationship and for inserting such assembly into a case regardless of whether the sides of the packages are bulged.

Yet another object of this invention is a provision of a case packing machine which is relatively simple in construction but capable of rapidly and efficiently performing its intended operation.

Still another object of this invention is the provision of a case packing machine having safety controls to prevent interfering operations from occurring.

It is another object of this invention to provide a machine for assembling a multiples of packages and inserting such multiples into a case, which machine may be easily and readily modified for operation with varying sizes of packages and cases.

Other objects and advantages will become apparent from the following description taken in connection with the accompanying drawings in which:

Fig. 1 is a perspective view of the machine of this invention;

Fig. 2 is a top plan view of the machine of Fig. 1;

Fig. 3 is an enlarged sectional view taken substantially along line 3—3 of Fig. 2;

Fig. 4 is a side elevational view of the machine of Fig. 1;

Fig. 5 is a semi-schematic view of selected mechanism of the machine of Fig. 1, before actuation of the side ram, showing the control circuit, the packages being shown in dot-dash lines;

Fig. 6 is an enlarged view of a portion of a mechanism of Fig. 5 showing the packages in solid lines;

Fig. 7 is a view similar to Fig. 6 after actuation of the side ram;

Fig. 8 is an enlarged sectional view, similar to Fig. 3, of a portion of a modified form of machine, taken substantially along line 8—8 of Fig. 9;

Fig. 9 is an enlarged top plan view, similar to Fig. 4, of a portion of the modified form of the machine of Fig. 8;

Fig. 10 is a semi-schematic view of selected mechanism of the machine of Fig. 8, showing the control circuit, the packages being shown in dot-dash lines;

Fig. 11 is an enlarged perspective view of the sequence relay of the circuit of Fig. 10; and,

Figs. 12 through 17 are schematic views illustrating steps of the method of this invention.

In general the method of this invention contemplates moving a line of packages or articles 1 (Fig. 12) of substantially uniform size and shape in a line 2 along a generally horizontal path of travel. A predetermined number of said articles, constituting a row 3, are elevated out of said line to form a tier 4 of articles 1 (Fig. 13). Successive tiers 4 are elevated one under the other to form a stack 5 of said tiers (Fig. 14). Stack 5 is then moved laterally of line 2, and after a succession of the previously described steps a case lot 6 (Fig. 16) is formed of a plurality of stacks 5. Upon formation of case lot 6, said case lot is inserted into case or shipping container 7 (Fig. 17) which is then removed to be closed and transported.

Therefore, the machine of this invention generally comprises means for performing these various steps of this method. The machine includes a generally horizontal input conveyor 10 (Figs. 2, 3, 4) for moving articles 1 and in line 2, and an elevator 11 (Figs. 2, 3) for elevating rows 3 of said articles to form tiers 4 and stacks 5. Said machine also includes a side ram 12 (Figs.

2, 3) for moving said stacks laterally of conveyor 10 for forming case lot 6 and inserting said case lots into cases 7. A case chair 13 and takeoff conveyor 14 (Figs. 1, 2, 4) are provided for transporting the filled case from the machine.

In detail, the machine of Figs. 1 through 4, comprises a generally rectangular housing 16 supported on adjustable legs 17. Said housing contains the major control and power equipment, such as motor 18 (Fig. 3) and forms a base for the greater portion of the structure of the machine. Extending from one side of housing 16 is input conveyor 10 which includes a belt 19, having a generally horizontal upper run, supported between pulleys 20, 21. Pulley 20 is supported at the outer end of a horizontally extending frame 22, the other end of which is secured to frame 16, and which is supported at its outer end by pedestal 23. Pulley 21 is supported for rotation on housing 16 and is driven by motor 18 through sprocket and chain drive 24 (Fig. 3). Articles or packages 1 are adapted to be moved in a line by conveyor 10 and two pair of guide rails 25, 26 (Figs. 3, 4) extend along either side of said conveyor for the purpose of maintaining said articles in a predetermined orientation.

Extending from the upper run of belt 19 at the end adjacent housing 16 is a short plate 27, rigidly secured to said housing. The top of elevator 11 is coplanar with said plate which acts to transfer the packages from belt 19 onto said elevator.

Elevator 11 comprises an elongated generally horizontal table 29 (Figs. 2, 3) having a bar 30 extending downwardly therefrom. Said bar is mounted in vertical guides 31 so as to be reciprocable therein. A double acting hydraulic cylinder 32 is mounted between bar 30 and the frame of housing 16 providing for such reciprocation. Table 29 may be formed of a single plate but preferably, to reduce friction, comprises an elongated, generally U-shaped frame 33 having a plurality of staggered rollers 34 mounted between the upstanding flanges 35 thereof. At the end of frame 33 remote from conveyor 10, a plate 36, having its upper surface coplanar with the tops of rollers 34, may extend between flanges 35 for providing a friction braking surface for packages traveling along said rollers.

Guide rails 25 extend along elevator table 29 to a vertical stop member 37 which is provided extending upwardly from said table adjacent plate 36. A line of articles traveling on the upper run of belt 19 is pushed across plate 27, onto table 29, and is stopped by member 37. For the purpose of this description the number of articles brought to rest on table 29 is denominated a row.

Depending from the edge of elevator table 29 adjacent conveyor 10 is a side plate 38 (Fig. 3). This plate, upon lifting of table 29, serves to hold the end of the line of articles or packages on conveyor 10 from forward motion until return of table 29 to a position coplanar with the upper run of belt 19.

Not only do both guide rails 25 extend the length of table 29, but the lower one of guide rails 26 also extends to stop member 37. Hence the articles, pushed by belt 19, are accurately guided onto table 19. To aid in stopping the row of articles on said table, an elongated friction rail 39 is positioned adjacent and parallel to upper guide rail 25. Rail 39 is yieldably urged toward the articles on table 29 by springs 28 (Figs. 5, 6, 7), and the end thereof adjacent conveyor 10 may be bent outwardly from the line of articles to avoid catching said articles on said end.

Spaced upwardly from one elongated side of elevator table 29 by an amount somewhat greater than the height of an article on said table, is side ram 12. Said side ram comprises a generally vertically extending plate 40 having a supporting bar 41 extending therefrom in a direction transversely of elevator table 29. Bar 41 is mounted for reciprocation in guide 42 which is secured atop hous-

ing 16 by brackets 43. Hydraulic cylinder 44 is mounted under guide 42 and has its piston rod pivotally connected to ear 45 on bar 41 for reciprocating said bar and attached plate 40 in response to actuation of cylinder 44.

Elevator 11 lifts successive rows of packages to form tiers 4, as previously explained, along the face of plate 40 of side ram 12. As each successive row is lifted it is held in position adjacent the face of side ram 12 and above table 29 of elevator 11 by an elongated carton dog 46 (Figs. 3, 5) which extends under the lower edge of plate 40. In this position the row becomes a tier. Dog 46 is supported at the end of a pair of bars 47 which are pivotally connected to the rear or inoperative face of plate 12. A tension spring 48 acting between plate 40 and an extension on bar 47 tends to urge the leading edge 49 of carton dog 46 to a position forwardly of the operative surface of plate 40 (Fig. 5). A cam surface 50 is provided adjacent the leading edge of dog 46 so that said dog will be cammed to a position flush with plate 40 by the row of articles upon elevation of said row. It is obvious that after the row (now a tier) of articles has been elevated past dog 46, said dog will snap under the lower edge of said tier to support the same. Another supporting member 51, to be later described, is provided at the edge of the tier of articles opposite plate 40 for a similar purpose.

Stop member 37 extends vertically throughout the height of plate 40 and therefore provides a guide for the edge of a stack of tiers of packages. Likewise guide member 52 positioned along the opposite edge of the stack and extending vertically from the top of the line of packages to the top of plate 40, serves to guide the adjacent edge of said stacks. The bottom end of member 52 may be bent slightly outwardly of said stack as shown in Fig. 3 so as to assure the correct positioning of the tiers as the same are raised by elevator 29.

In order that the case lot may be assembled of a plurality of such stacks before insertion into the case, and to aid in such insertion, a carton tube, generally designated 55 (Figs. 1, 2, 4), is supported in line with the direction of reciprocation of side ram 12. Said tube comprises a rectangular, centrally open frame 56 (Figs. 1, 2, 3, 4) supported, in a plane generally parallel to but spaced from plate 40, on housing 16 by braces 57. A thin plate is cantilevered from each side member of frame 56 to form an open ended box having the top 58, bottom 59, and sides 60. Bottom 59 is relatively fixed by bracket 61. Top plate 58 and side plates 60, however, converge slightly inwardly in a direction extending away from side ram 12. Each of the plates 58, 59 and 60 is provided at its end adjacent side ram 12 with an outwardly diverging lip 62 (Fig. 5) for guiding a stack of articles 1 into the carton tube. The converging side and top plates of said carton tube are slightly flexed apart by insertion of a stack therein so as to apply a restraining force to the sides of the stack in the end of the tube remote from side ram 12.

Case 7 is adapted to be slipped over the outer open end of carton tube 55 so that stacks urged through said carton tube by side ram 12 will be pushed into said case. The bottom or closed end of carton 7 is supported in the position shown in Fig. 5 by case chair 13. Said case chair comprises a bottom plate 65 (Fig. 4) and a side plate 66 (Fig. 2) adjoining each other at a generally right angle. Bottom plate 65 is centrally recessed as at 67 to form a generally U-shaped plate, for a purpose to be described.

Swingably secured to one edge of plate 65 by brackets 68 are a pair of fingers 69 (Fig. 2) for holding the bottom flaps 70 (Fig. 1) of case 7 closed and for yieldably urging said case onto tube 55. Said fingers are urged away from plate 65 and toward case 7 by a pair of tension springs 71 (Figs. 1, 2), which are secured at one end to the back of plate 65 and at the other end to eccentric

levers 72 which may be formed integrally with brackets 68.

Case chair 13 is supported at the end of bars 74 which extend from bottom plate 66 and are secured to pivot shaft 75 (Figs. 1, 5) supported for rotation in bracket 76. Crank arm 77 is secured at one end to shaft 75 and has its remote end pivotally secured to piston rod 78 of hydraulic cylinder 79.

In this manner reciprocation of piston rod 78 causes case chair 13 to rotate about shaft 75 from a position shown in solid lines in Fig. 5, where plate 66 is generally horizontal, to the dot-dash line position, where plate 66 is generally vertical. Takeoff conveyor 14 comprising a belt 80, having a generally horizontal upper run, mounted between pulleys 81, 82, is placed beneath case chair 13 in a position to receive cases 7 therefrom. Pulley 81 may be driven from motor 18 by universal shaft 83 (Fig. 2) and may be provided with takeup pulleys 84 (Figs. 1, 4). Pulleys 81, 82 are journalled for rotation on frame 85 which may be supported above the floor on pedestal 86. Said frame also mounts a plurality of rollers 87 which extend under the upper run of belt 80.

Bottom plate 65 of case chair 13 is cut away at a recess 67 so as to embrace the end of belt 80 when lowered onto said belt to be substantially coplanar therewith. In this manner, when case 7 has been filled, actuation of hydraulic cylinder 79 lowers chair 13 to belt 80 where said belt contacts the bottom of said case to move it from case chair 13. Guide rails 88 may be placed along either side of belt 80 and parallel thereto to prevent travel of case 7 off the side of said belt.

In operation reference will be made to the circuit and mechanism of Figs. 5, 6, and 7 as well as the previously described structure of Figs. 1 through 4. It is to be noted that an electric power source 91 is provided for the control circuit of Fig. 5 and the control solenoids 92, 94 and 99 of each hydraulic cylinder 32, 44 and 79, respectively, are grounded thereto. Cylinders 32, 44, and 79 are of a conventional type in which the advance and retard strokes of the piston are controlled by a slide valve operating at the command of such solenoids. Each said cylinder is also provided with a source of hydraulic power (not shown) which may be controlled manually by a valve 93 (Fig. 4).

As previously explained, starting with the machine empty, packages or articles 1 are moved in a line onto table 29 of elevator 11 by conveyor 10. When a row of said articles is in place on said table the end of said row contacts the blade of a conventional micro switch 95 (Figs. 3, 5). Switch 95 controls the advance stroke (denoted by the arrow *a*) of lift cylinder 32 and is normally spring urged to the inactive position. Upon contact by the row of articles on table 29 switch 95 is pushed to the active position completing the circuit between power source 91 and the advance side of solenoid 92. Hence cylinder 32 lifts elevator 11 to elevate the row 3 (Fig. 12) of articles on table 29 to a position A (Fig. 5), where such row becomes the bottom tier 4 held by carton dog 46 and supporting member 51.

Bar 30 of the elevator 11 has the lower end of switch actuator bar 96 (Fig. 5) attached thereto, which actuator bar has a curved upper end 97 and an intermediate hump 98. Switch 100 is in position to be actuated by hump 98 at the upper position of elevator 11 (see dot-dash line position, Fig. 5) and said switch then completes the circuit between power source 91 and the retard side of solenoid 92 (denoted by opposite arrow *r*). In this manner, when cylinder 32 has elevated the row of articles to position A, said cylinder returns elevator 11 to the bottom of its stroke (shown in Figs. 3, 5) as controlled by switch 100 and the retard side of solenoid 92. In the meantime, of course, switch 95 has returned to the inactive position to be activated by the second row of articles to be pushed onto table 29 by conveyor 10.

The above described operation of lifting a row of articles 1 to form a tier 4 adjacent the face of plate 40 of side ram

12 is then repeated. Upon the second elevating step, the row on table 29 lifts the tier at position A to position B (Fig. 5) and itself occupies position A. On the third such step, tiers at A and B are lifted to position B and C, respectively, and the third row becomes a tier at A, thus forming a stack 5 of a plurality of such tiers.

The machine thus far described is for use with regular boxes or articles having flat sides so that each tier 4 balances its adjacent tier without necessity for supporting the sides of the stack.

At this point the tier at position C contacts the blade of a micro switch 101 moving such switch from the dotted line position (Fig. 5), in which it completed the power circuit to the advance side of solenoid 92, to the solid line position in which such power circuit is interrupted. Hence, cylinder 32 is held inoperative while a complete stack 5 is in the position adjacent plate 40 shown in Fig. 5 (position C).

This movement of switch 101 also closes the circuit between power source 91 and the advance side *a* of solenoid 94 of cylinder 44 thereby actuating side ram 12 to push the adjacent stack 5 (at position C) to position D at the entry to the carton tube 55. The end of this stroke of side ram 12 is shown in Fig. 7, which together with Fig. 6 shows the detailed operation of supporting member 51.

Said member comprises a generally vertically disposed, elongated plate 103, generally parallel to table 29, the upper portion of which is curved in a direction toward side ram 12 to provide an inclined cam surface 104 extending partly into the upward path of the row of articles being lifted by elevator 11. The lower edge of plate 103 is secured to a horizontal shaft 105 (Figs. 4, 6, 7) which has its ends journalled in bearings 106 mounted on frame 56, so that plate 103 may be swung out of the way by the upward movement of said row of articles. A lever 107, also secured to shaft 105 for swinging therewith, has its end remote from said shaft connected to rigid arm 108 by tension spring 109. Said spring therefore urges cam surface 104 at plate 103 into the vertical path of the row of articles as shown in Fig. 6 and an adjustable stop 110 is provided on arm 108 abutting lever 107 for limiting such swinging of plate 103.

At its upper edge plate 103 is bent back from side ram 12 to provide a generally horizontal ledge 111 for supporting the edge of the bottom tier of articles that is opposite side ram 12 (Fig. 6). Secured to plate 103 under ledge 111, bearings 112 swingably support the stub shafts 113 which extend from either end of an elongated, vertically disposed lug 114. Said lug is yieldably urged to the vertical, against the edge of ledge 111 as a stop (Fig. 6), by torsion spring 115 (Fig. 4) which surrounds stub shaft 113 and is secured at either end to an outboard collar on said shaft and to plate 103.

As side ram 12 begins to move the stack at C into the entrance of the carton tube (position D, Fig. 6) lug 114 is pushed to a generally horizontal position by the tier of articles at A, against the force of spring 115. As such movement of the stack at C continues the lower edge of plate 40 of said side ram slides over lug 114 and then holds the same in the generally horizontal position against lip 62 of bottom plate 59 at the end of the stroke of side ram 12 (Fig. 7). At the same time carton dog 46 contacts cam surface 104 of plate

103 adjacent ledge 111 and swings said plate about the axis of shaft 105, against the force of spring 109. A stop 116 and an abutting adjustment screw 117 may be provided on arm 108 and lever 107, respectively, to limit the amount of swing of plate 103 in this direction.

Hence lug 114 affords a transition plate to support the stack being inserted into carton tube 55. It is obvious that upon retraction of side ram 12, both member 51 and carton dog 46 will snap back to the position shown in Figs. 5, 6, ready to receive another tier

of packages. The adjustability of member 51, provided by screws 110 and 117, and of carton dog 46, provided by an adjustment screw 118 (Fig. 6), enables the machine to be easily set for articles of different dimension.

Returning to Fig. 5, it will be noted that once the stack at C is moved away from the position shown by side ram 12, switch 101 will return to its dotted line position. To prevent operation of lift cylinder 32 at this time, reciprocable supporting bar 41 of side ram 12 is provided with a switch bar 121 which, upon reciprocation of bar 41, trips either of two switches 122, 123 at opposite ends of the stroke of the side ram. Switch 122 is interposed in the aforementioned power circuit of the advance side of solenoid 92 and is closed only when side ram 12 is in the retracted position. Once cylinder 44 drives side ram 12 to the left in Fig. 5, switch 122 breaks the power circuit to the advance side of solenoid 92 of the elevator cylinder.

Normally open, switch 123 controls the retard side r of solenoid 94 of cylinder 44 and is placed to be closed by switch bar 121 (dotted line position in Fig. 5) at the outer end of the stroke of side ram 12 (Fig. 7). Upon closing switch 123 completes the connection between power source 91 and the retard side of solenoid 94 to return side ram 12 to the position of Fig. 5.

It is also impossible for side ram 12 to be extended while elevator 11 is in its upper position (as at the upper end of the stroke that elevates the last tier in a stack) because of switch 124. This switch, normally closed, is also interposed in the power circuit of the advance side of solenoid 94 and is broken by contact with the upper end 97 of switch actuator 96 during the upper end of the stroke of lift cylinder 32. Once retraction of cylinder 32 and elevator 11 begins, switch 124 closes and the advance side of solenoid 94 is energized.

One other switch 125 is in the power circuit of the advance side of solenoid 94 to provide an additional safety factor. Switch 125 is normally open to interrupt such power circuit and is closed by bar 74 of the case chair lifting mechanism (Fig. 5). Hence, case chair 13 must be in its upper, case supporting position (shown in Fig. 5 in solid lines) before the advance stroke of side ram 12 can take place.

As previously explained, the open end of case 7 is slipped over carton tube 55. In this position (Fig. 5) an open, top flap 126, guided by bracket 61, strikes the blade of a micro switch 127 which is in the power circuit of the advance side a of solenoid 99 of chair cylinder 79. Assuming that case chair 13 is in the lowered position (shown in dot-dash lines in Fig. 5), it will be noted that a cutout switch 128, also in such power circuit, may be placed to be closed (dot-dash line position of switch blade) by said chair. Therefore, with case 7 in place on tube 55 and with chair 13 in the lowered position, the circuit between power source 91 and side a of solenoid 99 is completed to extend piston rod 78 of cylinder 79 and lift case chair 13 to a position supporting and backing up case 7.

As shown in Fig. 5, bottom plate 65 of said case chair is spaced from the bottom of case 7 by an amount less than the thickness of a stack 5 and fingers 69 are extended to hold bottom flaps 70 closed and case 7 in place on tube 55. Side plate 66 of chair 13 is slotted to pass the actuating lever of a switch 129, for a purpose to be described.

The steps thus far described of successively elevating rows of packages to form stacks of a plurality of tiers and successively moving said stacks laterally of elevator table 29 are repeated until stacks are assembled at positions C, D, E, and F (Fig. 5). Upon the next stroke of side ram 12, the stack at C is first consolidated with the others which are then pushed to the left until the stack at F reaches the bottom of case 7; then said case is urged away from carton tube 55 toward bottom

plate 65 of chair 13. As said side ram approaches the outer end of its advance stroke this movement of case 7 causes switch 127 to be opened, providing a second break in the power circuit to the advance side of solenoid 99.

At the same time case 7 closes switch 129 in the circuit between power source 91 and the retard side r of solenoid 99 thereby causing cylinder 79 to lower case chair 13 and place filled case 7 on belt 80 of takeoff conveyor 14. This ends one series of case-filling steps.

It will be noted that side ram 12 in its last above described stroke pushes the stacks at E and F out of carton tube 55 and into case 7. Said stacks are herein referred to as a case lot, and after such stroke of ram 12, the stacks at C and D (Fig. 5) are in position in the carton tube (Fig. 7) to be inserted into and carried away by the next case upon the next two strokes of side ram 12.

As mentioned before, the machine described with reference to Figs. 1 through 7 is for use with boxes or articles having substantially flat sides enabling them to support themselves in vertically stacked relationship. In order to process rounded or bulged packages or bags, such as those containing frozen foods, flour, sugar, and the like, the machine of this invention may be modified as shown in Figs. 8 through 10. The modification of Figs. 8 to 10 incorporates the basic structure of the previously described machine and such structure, including input conveyor 10, elevator 11, side ram 12, case chair 13, takeoff conveyor 14, and housing 16 and their component parts, is similarly referenced and operates in a similar manner.

Since the packages for which this machine is intended may be easily tipped over, such packages are adapted to be oriented with a long dimension in the direction of travel of conveyor 10. Table 29 of elevator 11 may as well be a single plate in this case.

One important difference in the modified machine lies in carton tube 130 (Figs. 8, 9). Such tube has a rectangular, vertically disposed, centrally open frame 131, supported by brackets 57 on housing 16, and a bottom plate 132 (Figs. 9, 10) cantilevered from frame 131 and supported by bracket 133, as in the machine of Figs. 4, 5. A pair of similar, vertically disposed side plates 134 are each secured at one edge, adjacent side ram 12, to a vertically elongated bar 135. Each said bar is mounted to frame 131 by a pair of bolts 136 fitting in loose holes in the vertical side members of said frame and each said bolt is surrounded by a helical spring 137 abutting bar 135 and said frame. This mounting not only allows side plates 134 to spring toward and away from each other but allows for limited swinging of said plates generally about the axis of the side members of frame 131.

A pair of leaf springs 138 are also secured to said side members of said frame and extend convergently in a direction opposite from side ram 12 along plates 134 to urge the end of the plates opposite bars 135 toward each other (Fig. 9). Both bottom plate 132 and side plates 134 are provided with flared lips 139 adjacent side ram 12 for guiding the stack of packages, pushed by said side ram, into carton tube 130.

Normally the packages being assembled by this modified machine are oriented with their shortest dimension parallel to the direction of travel through carton tube. The stacks of such packages and each column therein must be individually restrained by the carton tube because of the bulging sides of said packages and the differing dimensions thereof. To accomplish this individual restraint, in addition to the side plate structure described, the top of the carton tube 130 is composed of a plurality of individual similar, restraining assemblies 141, there being one assembly for each vertical column of packages in a stack.

Each assembly 141 comprises an elongated plate 142, mounted on frame 131 in the same manner as side plates 134 by bolts 143 and springs 144, and having a flared lip 145 (Fig. 10). A leaf spring 146, secured to said frame, similarly urges the remote end of each plate 142 toward bottom plate 132.

In addition, to assist in restraining the first stack of packages entering the carton tube and to facilitate such entrance a bent finger 147 extends from the entrance end of each plate 142. Said finger is mounted for swinging about a horizontal rod 148 (Figs. 8, 9, 10) and is provided with an eccentric lever 149 connected by tension spring 150 to frame 131 for urging the remote end 151 of finger 147 downwardly. When end 151 is pushed to the horizontal by a stack of packages (as at E, Fig. 10) it is substantially coplanar with plate 142. An adjustable stop 152 (Fig. 10) may be provided to abut lever 149 for limiting the downward movement of finger 147.

Another important difference in this modified machine exists in the mechanism for supporting the packages between successive elevations by elevator 11. Since the packages on which the modified machine operates may have bulged sides, said packages and tiers thereof will not be capable of supporting themselves in stacked relationship as in Fig. 5, position C. Hence, as the row of packages is lifted by elevator 11 (from position A, Fig. 10) it is tilted slightly toward side ram 12 by a horizontally elongated fixed plate 154. Plate 154 may be slightly bent along a horizontal line at two places intermediate its lower and upper edges so that its upper portion is slightly inclined to the direction of travel of elevator 11. Said plate is preferably of light gage spring steel and is secured at its lower edge to a guide rod 155 which is mounted on housing 16 opposite table 29 from guide rails 25 and intermediate the pair thereof. The upper edge of plate 154 is substantially even with and adjacent to bottom plate 132 of carton tube 130 and is formed with a lip 156 to guide the stacks of packages into the entrance of said tube.

Plate 154 is formed with a plurality of apertures 157 (Fig. 8), one for each vertical column of packages, for receiving therethrough one of the ends of a plurality of carton dogs 158. Each said dog is secured at its other end to a rotatable shaft 159 and is provided with a coil spring 160 urging said one end of said dog through said aperture and under the edge of each package of the tier raised to position B (Fig. 10) by elevator 11. It will be noted that the top of the tier at B is substantially even with bottom plate 132 of tube 130.

Opposite each carton dog is an arched, yieldable pad 161 which is pivotally mounted at one end of a lever 162. Each said lever is swingably mounted intermediate its ends to a shaft 163 and has its opposite end connected by a tension spring 164 (Fig. 10) to a portion of housing 16. Pads 161 are mounted adjacent the packages in the tier at position B and are urged against said packages by spring 164. Said pad may be urged to swing in one direction by a spring 165 connected between one edge of said pad and an extension 166 on lever 162 and an adjustable stop 167 is provided to limit the extent of such swing. The upper and lower edges of pad 161 are preferably curved to avoid interference with the packages.

Pads 161 tend to restrain the tier of packages at position B in the slightly inclined shown in Fig. 10 against plate 154. This causes the next higher tier (at position C) to be slightly tilted toward plate 40 of side ram 12 with its upper edge resting against such plate. The uppermost tier at D is supported by the tier at C in a substantially vertical position adjacent plate 40.

In operation, referring to Fig. 10, a row from the line of packages is moved onto table 29 by conveyor 10 to contact and close switch 95 (Figs. 8, 10) in a

manner similar to the machine of Fig. 5. With the rest of the machine empty switch 101 is in the dotted position, switch 122 is closed, and switch 95 therefore activates the advance stroke of lift cylinder 32.

5 The row of packages at A is lifted by elevator 11 to become a tier position B which tier is held there by dogs 158. Similarly, closing of switch 100 by hump 98 of actuator bar 96 retracts elevator 11. This elevating step is successively performed by the machine until tiers have been lifted to positions D, C, and B, as previously described.

At this point the upper tier of packages at D flips switch 101 to the solid line position to complete the circuit from power source 91 to the advance solenoid 159a of cylinder 44 and to the coil 169 of a sequence relay 170. One end of coil 169 is grounded. In addition to said coil, relay 170 (Fig. 11) includes a conventional armature 171 having a downwardly depending finger 172 adapted to engage a 9-point ratchet wheel 173, secured to a rotatably mounted shaft 174. Armature 171 is also provided with a stop element 175, adapted to contact ratchet wheel 173 to limit the rotation thereof.

25 Each time coil 169 is energized, armature 171 is attracted thereto, engaging finger 172 with ratchet wheel 173 to index shaft 174 one-ninth of a revolution. At its outboard ends shaft 174 is provided with three-lobe breaker wheels 176z, 176y, the lobes of each of which are adapted to break spring closed points 177z, 177y, respectively. Wheels 176z, 176y are set to perform three successive functions.

35 From the position shown in Fig. 11 in which points 177y are closed and points 177z are open, upon each successive energization of the relay; first, both points 35 are closed, second, points 177y are opened and points 177z close, and third, the points return to their original position, i.e. 177y closed, 177z open. These three successive functions are related to the operation of the machine as will be subsequently shown.

40 In contrast to the machine of Fig. 5, in which side ram 12 makes successive strokes of equal length, the side ram of the modified machine of Fig. 10 is adapted to make two short strokes and one long stroke in succession. As the machine is filled to the extent described with tiers of packages in a stack at D only, relay 170 should be in its original status shown in Fig. 11 and described above. The small, opposite side elevational views at Y and Z in Fig. 10 also illustrate the condition 50 of the points as does the small and elevational view at X.

The circuit from power source 91 through switch 122 (previously described as closed by switch bar 121 when side ram 12 is in the retracted position) and through 55 switch 101 (closed by the stack at D) may be traced to switch 124. This latter switch is normally closed upon retarding cylinder 32, as previously explained, which completes the power circuit to points 177y. Since said points are closed, current flows therethrough to 60 coil 169 of relay 170 and to the advance side a of solenoid 94 of cylinder 44. Side ram 12 is therefore actuated to the left in Fig. 10 and shaft 174 of relay 170 is indexed one-ninth revolution, closing both points 177y and 177z.

65 This modified machine is provided with two retard switches 123S and 123L for the short and long strokes, respectively, of side ram 12. Switch 123S is so placed to be closed by switch bar 121 upon the stack of packages at D reaching position E. At this point, closing 70 of switch 123S completes the circuit from power source 91, through said switch, and through points 177z (now closed) to the retard side b of solenoid 94, thereby reTRACTING side ram 12. During operation of side ram 12 elevator 11 is prevented from being lifted by cylinder 32 due to open switch 122.

11

After side ram 12 has completed its first short stroke, elevator 11 and again actuated to lift two more tiers of packages from positions A and B to form the second stack at positions C and D. Side ram 12 then makes a second short stroke, moving the stack at D to E and the stack at E to F (Fig. 10).

At the beginning of this second short stroke relay 170 is energized to rotate shaft 174 and open points 177y. To prevent this opening of points 177y from cutting the power to coil 169 before shaft 174 completes its full one-ninth turn, a micro switch 179 is mounted to be actuated by the movement of armature 171. When armature 171 is in its upper, spring held position (see X, Fig. 10) switch 179 is open and when armature 171 is pulled downwardly by coil 169 said switch closes. This switch is in a bypass circuit from coil 169 through switch 122 to power source 91. Hence, when armature 171 starts its downward movement to break points 177y, switch 179 closes, completing the power circuit to coil 169 until completion of the relay cycle opens switch 179.

After the third stack of packages is formed by elevator 11 at position D, side ram 12 is ready for its third and long stroke. Since points 177y are open the current from power source 91 must flow through switch 122, switch 101, switch 124, and switch 125 to coil 169 and advance solenoid 94a. Switch 125 is normally open and is closed by bar 74 when case chair 13 is in its upper position. However, when the machine is initially being filled with packages, case chair 13 is down and it is necessary to hold switch 125 closed by hand for the first long stroke of side ram 12.

When this long stroke of the side ram is initiated relay 170 is actuated, indexing shaft 174 to break points 177z and close points 177y (the condition shown in X, Y, and Z of Fig. 10 and Fig. 11). It will be noted that breaking points 177z inactivates switch 123S which will be bypassed by switch bar 121. Instead, side ram 12 will travel the full stroke of cylinder 44 until the retard side of solenoid 94 is energized by bar 121 contacting and closing switch 123L. This long stroke first consolidates the stack at D with E and F stacks to form a case lot and then pushes said lot to the position indicated at G, H and I in Fig. 10.

Subsequently, the steps of assembling stacks at D and moving said stacks to E and F are automatically repeated during the second cycle of the machine. At the end of the second short stroke of ram 12 in this second cycle it is necessary to place case 7 on carton tube 130. Top flap 126 of said case closes switch 127, as previously described, actuating the advance side A of solenoid 99 to cause cylinder 79 to raise chair 13 from the dot-dash line position to the upper, solid line position of Fig. 10. This lifting of chair 13 closes switch 125 and the long stroke of ram 12 may take place.

Such long stroke pushes the stacks at G, H, and I into case 7, and the case is pushed out to contact and close switch 129 for activating retard solenoid 99r. Chair 13 then lowers the filled case to belt 80 of takeoff conveyor 14. At the same time the second lot of packages at D, E, and F have been pushed to G, H and I.

As the filled case is lowered to conveyor 14 another empty case is placed on tube 130 and stacks of packages continue to be assembled at positions D, E and F. Three stacks of packages remain in the tube continually at positions G, H and I and the described steps automatically performed in the correct sequence.

It will be noted that both of the modifications of the machine of this invention may be easily adjusted and/or altered slightly for handling packages and cases of different dimensions. In fact one modification can be converted to the other by replacing only a few parts.

The novel method which the machine performs is diagrammatically illustrated in Figs. 12 through 17. It is obvious that such method can as well be performed by

12

mechanism, other than that specifically described, or by hand. Fig. 12 shows the first step in the method of loading a row 3 of articles 1 on the elevator from the line 2 of said articles on conveyor 10. Row 3 is elevated to form tier 4 (Fig. 13) and this second step is repeated until a predetermined number of tiers 4 have been elevated to form stack 5 (Fig. 14). Stack 5 is then moved laterally of line 2, as seen in Fig. 15, and the steps of Figs. 13 and 15 successively repeated until a case lot 6 of a plurality of stacks 5 are formed (Fig. 16). In the last step, said case lot is inserted in case 7.

Although the invention has been described and illustrated in detail, it is obvious that modifications could be made therein without departing from the spirit and scope of the invention.

I claim:

1. In a method for packing a generally rectangular case with articles of substantially uniform size and shape, the steps of: moving said articles in a line along a generally horizontal path of travel, successively vertically elevating rows of a predetermined number of said articles from said line to form a stack of a predetermined number of generally vertically aligned tiers in a plane including said line, and successively moving said stacks laterally of said path to form a case lot of a plurality of said stacks for insertion into said case, and applying a yieldable restraining force to at least two sides of said lot during said lateral movement.

2. In a method for packing a generally rectangular case with articles of substantially uniform size and shape, the steps of: moving said articles in a line along a generally horizontal path of travel, successively vertically elevating rows of a predetermined number of said articles from said line to form a stack of a predetermined number of generally vertically aligned tiers, supporting the lowermost of said tiers between successive elevations, each of said tiers supporting the tier thereabove inclining at least one of said tiers in said stack from the vertical, supporting said stack on the downwardly directed inclined side during such inclination, and successively moving a portion of said stack laterally of said path to form a case lot of a plurality of said portions of said stacks for insertion into said case.

3. In a method of packing a generally rectangular case with articles of substantially uniform size and shape, the steps of: moving said articles in a line along a generally horizontal path of travel, successively vertically elevating rows of a predetermined number of said articles from said line to form a stack of a predetermined number of generally vertically aligned tiers, supporting the lowermost of said tiers between successive elevations, each of said tiers supporting the tier thereabove, including at least one of said tiers in said stack supporting said stack on the downwardly directed inclined side during such inclination, successively moving a portion of said stack laterally of said path to form a case lot of a plurality of said portions of stacks, and pushing said case lot into said case by the formation of the next case lot.

4. A machine for packing articles of substantially uniform size and shape in a generally rectangular case comprising: elevator means, feeder means for moving a row of a predetermined number of said articles into position to be acted upon by said elevator means, said elevator means being successively operable for elevating a predetermined number of said rows, one under the other, to form a stack of generally vertically aligned tiers in the plane of operation of said elevator means, holding means for supporting said tiers between successive elevations, and pusher means for successively moving said stacks laterally of said tiers to form a case lot of said stacks and for inserting said case lot into a case, and yieldable restraining means on at least two sides of said case lot for preventing toppling of said stacks prior to insertion into said case.

5. In a case filling apparatus, a conveyor for moving

articles of uniform shape and size in a line along a horizontal path of travel in one direction, an elevator positioned in alignment with said conveyor for receiving a predetermined number of such articles thereon in a horizontally extending row, means for displacing said elevator out of alignment with said conveyor for positioning said row in a tier in a generally vertical plane including said line and spaced vertically from said path, means for automatically holding said tier in said spaced position when said elevator is retracted to said position in alignment with said conveyor, said elevator being successively operable for positioning successive rows to form a stack of a plurality of said tiers in said plane, a generally rectangular, open ended tube spaced horizontally from said plane and in line with said stack, pusher means, reciprocable laterally of said vertical plane, for successively inserting said stacks into one end of said tube and consolidating said stacks therein to form a case lot of a plurality of said stacks, the other end of said tube being adapted to be inserted in the open end of a case to be filled, case supporting means mounted for swinging movement between a position supporting the closed end of the case on said tube and a position supporting such case in upright condition and depositing the same on a take off conveyor and including yieldable means yieldably engaging the closed end of such case, further reciprocations of said pusher means urging said case lot through said tube and into said case and case outwardly of the end of said tube and against the yieldability of said yieldable means, and means responsive to said outward movement of said case for initiating said swinging movement.

6. In a case filling apparatus, a conveyor for moving articles of uniform shape and size in a line along a horizontal path of travel in one direction, an elevator positioned in alignment with said conveyor for receiving a predetermined number of such articles thereon in a horizontally extending row, means for displacing said elevator out of alignment with said conveyor for positioning said row in a tier spaced vertically from said path, means for automatically holding said tier in said spaced position, when said elevator is retracted to said position in alignment with said conveyor, said elevator being successively operable for positioning successive rows to form a stack of a plurality of said tiers in a generally vertical plane, means for slightly tilting at least one of said tiers, and means for supporting said stack on the downwardly directed inclined side of said tilted tier.

7. A machine for packing articles of substantially uniform size and shape in a generally rectangular case comprising: elevator means, feeder means for moving a row of a predetermined number of said articles into position to be acted upon by said elevator means, said elevator

means being successively operable for elevating a predetermined number of said rows, one under the other, to form a stack of generally vertically aligned tiers, and pusher means for successively moving said stacks laterally of said tiers to form a case lot of said stacks and for inserting said case lot into a case, and interlocking control means initiated by said articles for controlling the successive operations of said elevator means and said pusher means and for preventing interference therebetween, said control means including a sequence relay for determining the sequence of operation of said pusher means.

8. A machine for packing articles of substantially uniform size and shape in a generally rectangular case comprising: a generally horizontally extending feeder conveyor for moving a plurality of said articles in a line in one direction, elevator means elongated in said one direction and aligned with said conveyor for receiving an elongated row of a predetermined number of said articles from said conveyor, said elevator means being successively vertically operable for elevating a predetermined number of said rows one under the other to form a stack of generally vertically aligned rows in the plane of operation of said elevator means, holding means disposed above and longitudinally of said elevator means for receiving each said row from said elevator means and for supporting the same along the opposed longitudinal edges thereof, and pusher means successively operable transversely of said elevator means and disposed thereabove for successively shifting said stacks transversely of said rows to form a case lot of a plurality of said stacks.
